Primary Examiner — Mark Goodwin*(74) Attorney, Agent, or Firm* — Cynthia Miller(57) **CLAIM**

The ornamental design for a fragrance bottle and cap, substantially as shown and described.

DESCRIPTION

FIG. 1 is a top front right side perspective view of my new design for a fragrance bottle and cap;

FIG. 2 is a front elevation view of the fragrance bottle and cap shown in FIG. 1, the rear elevation view being identical thereto;

FIG. 3 is a right side elevation view of the fragrance bottle and cap shown in FIG. 1, the left side elevation view being identical thereto;

FIG. 4 is a top plan view of the fragrance bottle and cap shown in FIG. 1; and,

FIG. 5 is a bottom plan view of the fragrance bottle and cap shown in FIG. 1.
